UNITED STATES PATENT OFFICE.

ERNEST KIRCHHOFF, OF GREAT KILLS, NEW YORK, ASSIGNOR TO GOLDING BROS. COMPANY, OF NEW YORK, N. Y., A CORPORATION OF NEW YORK.

DESIGN FOR A TEXTILE FABRIC.

Application filed January 25, 1924. Serial No. 8,420. Term of patent 3½ years.

To all whom it may concern:

Be it known that I, ERNEST KIRCHHOFF, the textile fabric embodying my new design, a citizen of the United States, residing at Great Kills, Staten Island, New York city, in the county of Richmond and State of New York, have invented a new, original, and ornamental Design for Textile Fabric, of which the following is a specification, reference being had to the accompanying drawings, forming a part thereof.

The figure is a plan view of a section of the textile fabric embodying my new design.

I claim:

The ornamental design for a textile fabric, as shown.

ERNEST KIRCHHOFF.
